CLAIM

The ornamental design for a dishwasher front panel, as shown and described.

DESCRIPTION

FIG. 1 is a front perspective view of a dishwasher front panel showing our new design;

FIG. 2 is a right side elevational view thereof, the left side being a mirror image thereof;

FIG. 3 is a top plan view thereof; and,

FIG. 4 is a front elevational view thereof.

The rear of the dishwasher front panel is plain and unornamented.

FIG. 1

FIG. 2

FIG. 3

FIG. 4
